DISPENSER

Michael C. Sawchuk, Toronto, Ontario, Canada

Application March 7, 1949, Serial No. 1,262

Term of patent 14 years

(Cl. D4—3)

To all whom it may concern:

Be it known that I, Michael C. Sawchuk, a citizen of the Dominion of Canada, residing in the city of Toronto, in the county of York, in the Province of Ontario, Canada, have invented a new, original, and ornamental Design for Dispenser of which the following is a specification, reference being had to the accompanying drawing, forming a part thereof.

In the drawings:

I claim:

The ornamental design for a dispenser, substantially as shown.

MICHAEL C. SAWCHUK.
